UNITED STATES PATENT OFFICE

2,655,155

INFRARED RAY, INDIRECTLY HEATING
HEAT BATH

Martin Achner, Munich, Germany

Application June 20, 1951, Serial No. 232,649
In Germany June 22, 1950

8 Claims. (Cl. 128—374)

1

The present invention relates to an improved construction for a heat bath, more particularly to a heat bath which may be collapsed for storage and transportation and by which a person is indirectly heated by infra-red rays.

Conventional collapsible heat baths comprise thin wooden walls or walls made up of impregnated fabric or insulating material supported by frames, and are heated either inside by electric stoves or by hot gases produced outside of the bath. In such heat baths, not more than 40 per cent of the produced heat is transferred to the body of the person in the bath, the balance of the heat being lost by convection and radiation.

It is an object of the invention to provide a heat bath construction which is economical because it does not waste any appreciable amount of heat.

A further object of the invention is the provision of a heat bath which can be collapsed, more particularly rolled into a roll of small diameter for transportation and storage.

Another object of the invention is the provision of a heat bath which does not have metallic parts and surfaces which become so hot as to cause burns upon contact. The heat bath according to the invention is lined inside with a heat-reflecting metal foil which is so thin that it cannot accumulate enough heat to cause burns upon contact. The foil may be made of aluminum, silver, copper, or other suitable metal which is highly polished or otherwise made heat- and light-reflecting on the surface which faces the interior of the heat bath. The high heat-reflecting effect and extremely small mass of the thin foil not only prevents accumulation of enough heat to cause burns but also prevents absorption of heat by the wall construction supporting the foil, so that no heat is transferred to the outside of the bath and lost.

A further advantageous effect of the mirror-like metallic surface is that the infra-red rays from a heater arranged inside the bath are reflected to the body of the person taking the bath, penetrating deeply into the body. Ultra-red rays pass through air without appreciably heating it, i. e. without heat loss. The heat flows freely into the body and heat congestion causing discomfort is avoided.

Further and other objects of the present invention will be hereinafter set forth in the accompanying specification and claims, and shown in the drawing which, by way of illustration, shows what I now consider to be preferred embodiments of my invention.

2

In the drawing:

Fig. 1 is a sectional view of a wall portion of the heat bath according to the invention;

Fig. 2 is a sectional view of a wall portion of a modified construction;

Fig. 3 is a sectional elevation of a heat bath according to the invention;

Fig. 4 is a sectional plan of the heat bath according to Fig. 3;

Fig. 5 is a perspective view of the bath shown in Figs. 3 and 4 in rolled up condition.

Like parts are designated by like numerals in all figures of the drawing.

The interior surface of the wall forming the heat bath is covered by a thin metal foil 1, for example of aluminum, silver, copper, nickel, tin, or similar material, whose outside surface is highly polished and whose thickness is one hundredth to three hundredths of a millimeter.

In the modification shown in Fig. 1, the foil is applied to a cardboard 2 forming the inside of an insulating wall, by pressing, pasting, or other method assuring intimate contact of the cardboard and foil. The cardboard 2 is mounted with an adhesive 3 on a rubberized fabric or rubber layer 4, the latter being reinforced by battens 5 of U-shaped cross-section which enclose air cells 6. The so constructed wall is thin and capable of being rolled into a roll of small diameter, as shown in Fig. 5, to facilitate storage and transportation.

In the modification shown in Fig. 2, the foil 1 is applied to a cardboard 2 which is mounted with an adhesive 3 on leatherboard 7 which is backed by a sheet 9 of synthetic material with which it is connected by an adhesive layer 8. This construction is sufficiently heat-insulating to permit omission of air cells and is sufficiently flexible to be rolled into a small diameter roll.

The shape of the bath, when in use, may be cylindrical as shown in Figs. 3 and 4. This shape is preferred because its interior volume and space requirement is 30 per cent less than if the wall is formed to have a quadratic or rectangular cross-section, although the latter shape, with well-rounded corners, is easily possible with the wall construction according to the invention.

Fig. 4 shows how an electric heater H can be placed within the bath and how the heat waves are reflected and absorbed by the treated person.

While I believe the above described embodiments of my invention to be preferred embodiments, I wish it to be understood that I do not desire to be limited to the exact details of design and construction shown and described, for

obvious modifications will occur to a person skilled in the art.

I claim:

1. A collapsible infra-red ray indirectly heating heat bath comprising a flexible wall, and a polished metal foil attached to the inside of said wall and capable of efficiently reflecting infra-red rays, the thickness of said metal foil being less than three hundredths of a millimeter.

2. A collapsible heat bath according to claim 1, said wall including a lamina of continuous flexible material and a layer of juxtapositioned unconnected battens having a U-shaped cross-sectional configuration and being so connected with said lamina that the opening of the U is closed by said lamina.

3. A collapsible heat bath according to claim 1, said wall having a plurality of cavities forming air cells.

4. A collapsible heat bath according to claim 1, said wall comprising a lamina made of cardboard, and a lamina containing rubber and being glued to the lamina made of cardboard, said metal foil being attached to the latter.

5. A collapsible heat bath according to claim 1, said wall comprising a lamina made of cardboard, a lamina containing rubber and being glued to the lamina made of cardboard, and a plurality of juxtapositioned battens connected with said lamina containing rubber, said metal foil being attached to the lamina made of cardboard.

6. A collapsible heat bath according to claim 1, said wall comprising a first lamina made of card-

board, a second lamina made of leather material glued to said first lamina, and a third lamina made of synthetic material glued to said second lamina, said metal foil being attached to said first lamina.

7. An infra-red ray indirectly heating heat bath comprising a seat, an electric heater disposed underneath said seat, and a wall spaced from and disposed all around said seat, said wall being made of heat-insulating material and having an inner surface covered with a highly polished metal foil capable of reflecting infra-red rays from said heater to the person sitting on said seat, said metal foil being so thin that it is unable to accumulate enough heat to cause burns upon contact and said heater forming the only source of heat for the heat bath.

8. A collapsible heat bath according to claim 1, said wall being constructed for great resistivity to heat conduction.

MARTIN ACHNER.
